ATTORNEY.

UNITED STATES PATENT OFFICE

2,413,530

SCOOTER CONSTRUCTION

William W. Taylor, San Marino, Calif.

Application November 7, 1944, Serial No. 562,319

5 Claims. (Cl. 280—87.04)

1

This invention has to do with children's vehicles of the "scooter" type comprising a base carrying forward and rear pairs of wheels and a post at the forward end of the base, and has for its general purpose to improve such vehicles in several important respects concerning both their structure and operating characteristics.

One major object is to provide a novel base and post construction giving the vehicle desirable light weight, and yet great strength that will withstand rough usage. This purpose is served by forming preferably both the base and post with an interfitting channel construction rendering the vehicle capable of economical manufacture without sacrificing the essential qualities of lightness and strength.

The invention further contemplates a novel association of the wheel mountings with relation to the top and bottom base channels, in accordance with which the mountings are attached in concealed locations to the underside of the top channel beyond the ends of the lower channel.

Another object is to provide a simple form of wheel mounting whereby the wheel pairs are caused to turn horizontally in response to lateral tilting of the base, and in this manner enable the vehicle to turn on different radii determined simple by the degree of inclination given the vehicle by the rider.

The various features and objects of the invention will be fully understood from the following description of a preferred embodiment of the invention shown in the accompanying drawing, in which:

Fig. 1 is a view showing the vehicle in perspective;

Fig. 2 is an enlarged cross-section on line 2—2 of Fig. 1;

Fig. 3 is a fragmentary section on line 3—3 of Fig. 2; and

Fig. 4 is a cross-section on line 4—4 of Fig. 3.

In its general form and construction, the vehicle comprises an elongated base 10 carrying forward and rear pairs of wheels 11 and 12, and a post structure 13 at the forward end of the base. As shown in Figs. 2 and 3, the base 10 is formed as a light-weight, rigid unit comprising a full length upper channel 14 with depending side flanges 15, and a bottom channel 16 received and interfitting within the upper channel. As will be understood, the two channels may be welded or otherwise secured together at suitable locations to form, in effect, a double-channel beam. As illustrated in Figs. 1 and 3, the lower channel 16 terminates at distances from the ends of channel

2

14 sufficient to accommodate the wheel mountings, generally indicated at 17, and permit their application directly to the under surface of the top channel.

5 The post structure 13 comprises a forward channel 18 which overlaps and is welded at 19 to the side flanges 15 and channel 14. Received and interfitting within channel 18 is a rear channel 20, the bottom portion of which is turned at 21, 10 see Fig. 3, for welding or other attachment to the top surface of channel 14. The post carries at its upper end a transverse handlebar 22 held in place by a metal strap 23 secured by screws 24 to the two channels.

15 As previously indicated, the wheels are mounted at 17 in a manner such that the individual wheel pairs are caused to turn horizontally on the road surface in response to lateral tilting of the base and post assembly. As illustrative of a 20 simple and effective mounting construction, the latter is shown to comprise a bracket 25 secured at 26 and 27 to the channel 14 carrying a pin 28 positioned in the vertical plane of the base axis and inclined longitudinally thereof, substantially 25 as illustrated. The wheels 29 rotate on axle 30 which is attached at 31 to a yoke 32 pivotally carried by the pin 28.

By virtue of the angular position of the pin 28 on which the wheel and yoke assembly turns, 30 lateral tilting of the base to the left or right, produces respectively left or right turning of the pair of wheels. Accordingly, the rider, in order to turn the vehicle in an arc, has only to throw his weight to one side or the other of a balanced 35 position, and obviously, the greater the lateral tilting of the base, the sharper will be the turns effected by the wheels.

I claim:

1. A scooter-type vehicle comprising top and 40 bottom interfitting channels forming a base, said channels being reversely positioned with their side flanges interengaged, forward and rear pairs of wheels connected to the under side of said top channel beyond the ends of the bottom channel, 45 and a post at the forward end of the base.

2. A scooter-type vehicle comprising top and 50 bottom interfitting channels forming a base, said channels being reversely positioned with their side flanges interengaged, forward and rear pairs of wheels connected to the under side of said top channel beyond the ends of the bottom channel, the side flanges of said top channel depending below the top portions of said wheels, and a post at the forward end of the base.

3. A scooter-type vehicle comprising top and

bottom interfitting channels forming a base, said channels being reversely positioned with their side flanges flatly interengaged, front and rear interfitting channels forming a post at the forward end of the base, the last mentioned channels being reversely positioned with their side flanges flatly interengaged, said top channel extending beyond said rear channel and being attached to said forward channel and said rear channel being attached to said top channel, and front and rear pairs of wheels connected to said base.

4. A scooter-type vehicle comprising top and bottom interfitting channels forming a base, said channels being reversely positioned with their side flanges flatly interengaged, front and rear interfitting channels forming a post at the forward end of the base, the last mentioned chan-

nels being reversely positioned with the side flanges flatly interengaged, and front and rear pairs of wheels connected to the underside of said top channel beyond the ends of said bottom channel.

5. A scooter-type vehicle of the character described, comprising top and bottom reversely positioned interfitting channels forming a base, forward and rear pairs of wheels connected to the underside of said top channel beyond the ends of the bottom channel, and a pair of reversely positioned interfitting channels attached to and forming a hollow post at the forward end of said base, the side flanges of one of the last mentioned channels being in overlapping relation with the side flanges of said top channel.

WILLIAM W. TAYLOR.
